(No Model.)

M. VIRNOCHE.
GAME APPARATUS.

No. 411,402.

Patented Sept. 17, 1889.

UNITED STATES PATENT OFFICE.

MAXIME VIRNOCHE, OF WOONSOCKET, RHODE ISLAND, ASSIGNOR OF
THREE-FOURTHS TO LOUIS LEMONDE, JEMENGIO BOUINO, AND FER-
DINAND CREPEAU, OF SAME PLACE.

GAME APPARATUS.

SPECIFICATION forming part of Letters Patent No. 411,402, dated September 17, 1889.

Application filed May 28, 1889. Serial No. 312,406. (No model.)

To all whom it may concern:

Be it known that I, MAXIME VIRNOCHE, a citizen of the United States, residing at Woonsocket, in the county of Providence and State 5 of Rhode Island, have invented certain new and useful Improvements in Game Apparatus; and I do declare the following to be a full, clear, and exact description of the invention, such as will enable others skilled in the art 10 to which it appertains to make and use the same.

This invention relates to an improvement in game-boards, and the novelty will be fully understood from the following description 15 and claims, when taken in connection with the accompanying drawings, in which—

Figure 1 is a longitudinal sectional view of my improved board with the balls or marbles in position, and the gun, such as employed 20 in the game, illustrated. Fig. 2 is a plan view showing the position of the wire guard in dotted lines.

Referring by letter to said drawings, A indicates a board preferably of elongated rect- 25 angular form. This board is of any suitable size and has a smooth upper surface.

a indicates a marginal guard-wall arranged vertically, so as to retain the balls or marbles upon the board. This board is also provided 30 near one end with recesses, as shown at b, adapted to receive the balls or marbles, and with lateral pockets c, for a similar purpose. These recesses and pockets, which are ar- 35 ranged near one end of the table, are pro- tected by a hood or guard B, formed from wire-gauze or other suitable material which will adapt or afford inspection of the balls or marbles and yet prevent handling of them without detection. This gauze guard is ar- 40 ranged upon the table so as to extend suffi- ciently high that it will not interfere with the free movement of the marbles on the board, and the entrance portion preferably flares, as shown at d. The guard is also provided in 45 its roof or top with an annular opening, as shown at e, so as to permit a person setting the balls or marbles, such as in the game of pool. By this construction it will be seen that when the marbles or balls have been fired,

as will be presently explained, they will be 50 prevented from leaving the table, as the wire guard will retain them upon the board, the marginal skirt-flange assisting when the marbles have been driven from beneath the wire-work. 55

The board may be placed upon a table or other suitable support, or in some cases it may be mounted upon legs, such as an ordinary billiard or pool table.

In operation the attendant nests the balls 60 by access through the opening in the wire shield or guard in the position as shown. The player, who should be stationed from eight to ten feet from the marbles on the board, takes a gun such as shown and shoots 65 at the marbles with a rubber or other suitable ball, the marbles being numbered. Those entering the pockets are counted toward the game by the numbers they represent.

The gun which I employ, as indicated by 70 Z, is designed to be a spring-actuated or air gun, as by the use of such there will be no report or excitement caused at the firing, and it may be operated by any person with- 75 out experience, there being nothing about it which may get out of order.

Having described my invention, what I claim is—

1. The combination, with a game-board having a bank and side pockets, of a guard 80 composed of wire-work arranged over the board and above the pockets therein, and also having a central opening in its roof, sub- stantially as and for the purpose specified.

2. The combination of a game-board hav- 85 ing a vertical marginal guard-wall, and a guard arranged across the table and above the pockets and recesses therein, the said guard having an opening in its roof to per- mit of the introduction of the arm to the 90 board, substantially as specified.

In testimony whereof I affix my signature in presence of two witnesses.

MAXIME VIRNOCHE.

Witnesses:

GEO. W. SPAULDING,
SAM'L. P. COOK.
